E. J. TOBIN

DRINKING WATER SERVING OLLA

Filed April 3, 1928

INVENTOR.

Edmund J. Tobin

BY

W. J. Fitzgerald ATTORNEY.

UNITED STATES PATENT OFFICE.

EDMUND J. TOBIN, OF ALTADENA, CALIFORNIA.

DRINKING-WATER-SERVING OLLA.

Application filed April 3, 1928. Serial No. 266,913.

My invention relates to ollas for drinking water and it has for its principal object to provide means whereby the olla is kept full of water at all times so that the evaporation takes place over the entire surface of said olla instead of only a portion thereof, as is the case when the arrangement is such that the contents do not completely fill said olla.

It is known that as the water percolates through the porous body of an olla and evaporation takes place on the surface thereof, that said body is kept clean, but the upper part of the olla is not filled with water owing to the fact that the upper bottle, or other receptacle for the original supply of water extends down into the olla some little distance, and water does not rise in the olla above this point, leaving the upper part of the olla empty. As a result, this part of the body of said olla has no evaporation action and becomes clogged and discolored and unsightly and unsanitary. Then it is also impossible to tell how low the water is in the olla without removing the upper reservoir and inspecting the inside of the olla.

I have conceived an improvement which makes possible and practical two advantages and eliminates the objections above mentioned. I have conceived the idea of interposing an intermediate member, preferably of heavy glass, between the top of the olla and the upper reservoir, or bottle of water, which holds said reservoir or bottle above the top of the olla, thus filling it with water to the very top and even up into the intermediate member, and at the same time makes it possible to see clearly how high the water is, should the bottle be empty, without removing any of the upper containers.

In order to fully explain my invention, I have shown one practical embodiment thereof on the accompanying sheet of drawings, which I will now explain.

The figure is a side elevation of a complete outfit, partly in section, embodying my invention.

Referring now in detail to the drawing, 2 designates an olla, which is understood to be a porous earthen jar for drinking water which is kept cool by evaporation from the outer surface, and it is provided with a faucet 3, and is set into a dish 4, with an offset flange 5, whereby the evaporation drippings running down the outside of said olla are caught in said dish 4.

The top of said olla 2 is formed to receive the lower edge 6, of an intermediate member 7. This is cemented into place, as at 8, whereby to make a water tight joint.

In the present showing, I have indicated 60 the usual water bottle 9, inverted and set into the open upper end of said intermediate member 7, with any suitable cushion or gasket, as 10, around the upper edge of said intermediate member 7. Said intermediate member 65 7 is shown of heavy glass, sufficiently strong to carry the bottle of water 9, and to hold it so that the neck and mouth of said bottle is held above the top of said olla, as at 11, the water filling the olla and rising into 70 the intermediate member, substantially as indicated in the drawings.

It will thus be seen that the olla is completely filled with water and that the water can be seen in the intermediate member 7, 75 without removing any of the parts of the apparatus. This makes it certain that the action of evaporation will take place over the entire surface of the olla and that there will be no portion thereof to become discolored or 80 clogged with deposit or foreign matter, and at the same time giving an attractive appearance to the apparatus because of the clear glass intermediate member into which the water rises.

It will be understood, of course, that other reservoir for the original supply of water can be used instead of the bottle, and I do not limit my invention to the particular showing here made for descriptive purposes, except as 90 I may be limited by the hereto appended claims.

I claim:

1. In combination, an olla for drinking water, an intermediate member secured into 95 the upper end thereof with a water tight joint, and adapted to support a reservoir of water therein and above the top of said olla, and a reservoir of water set into said intermediate member with its lowermost part 100 above the top of said olla, whereby water completely fills said olla and rises into said intermediate member.

2. In combination, an olla for drinking water, an intermediate member of glass secured in the upper open end of said olla, and a water reservoir set into said intermediate member and supported thereby with its lowermost part above the top of said olla, whereby water rises into said intermediate 110

member and is visible through the side thereof, substantially as and for the purpose described.

3. An olla for drinking water having means for holding a reservoir of water above the top of said olla, said means being adapted to permit water to rise above the topmost part of the olla proper, whereby to make possible evaporation over the entire outer surface of said olla, for the purpose described.

4. In combination, an olla for drinking

water, a glass member secured in its top and adapted to support a water bottle inverted therein and holding the mouth of said bottle above the top of said olla, whereby water from said bottle rises above the top of said olla, for the purpose described.

Signed as Los Angeles, Los Angeles County, California, this 29th day of March, 1928.

EDMUND J. TOBIN.
